UNITED STATES PATENT OFFICE.

JOHN LINES, OF WATERBURY, CONNECTICUT, ASSIGNOR TO THE SCOVILL MANUFACTURING COMPANY, OF SAME PLACE.

GUDGEON FOR WINDOW-SHADE ROLLERS.

SPECIFICATION forming part of Letters Patent No. 325,422, dated September 1, 1885.

Application filed January 26, 1885. (No model.)

To all whom it may concern:

Be it known that I, JOHN LINES, of Waterbury, in the county of New Haven and State of Connecticut, have invented a new 5 Improvement in Gudgeons for Window-Shade Rollers; and I do hereby declare the following, when taken in connection with accompanying drawings, and the letters of reference marked thereon, to be a full, clear, and exact 10 description of the same, and which said drawings constitute part of this specification, and represent, in—

Figure 1, a side view of the cup and gudgeon complete; Fig. 2, a side view of the gudgeon as prepared for attachment to the cup; Fig. 3, a longitudinal section through the cup, showing the gudgeon as introduced ready for setting; Fig. 4, the same view, the enlargement set to form the outside flange of the 20 gudgeon.

This invention relates to an improvement in the gudgeon which forms a pivot upon which shade-rollers turn, and to that class in which the gudgeon is attached to a cup constructed to be set on over the end of the roller, and is an improvement upon the invention for which Letters Patent No. 298,611 were granted to the assignees in this application, the invention relating especially to the method of securing the gudgeon to the cup; and the invention consists in constructing the gudgeon with a head upon one end and an enlargement immediately under the head, the body of the gudgeon introduced through the cup from the 25 inside to bring the head to a bearing thereon, the enlargement extending through the hole in the cup, the projecting portion of said enlargement then struck down onto the outside of the cup around the hole, as more fully herein- 30 after described.

A represents the cup, which corresponds in internal diameter to the diameter of the roll, so as to set on over the end, and so that the bottom of the cup may come against the end 45 of the roll. Centrally in the bottom of the cup a hole, *a*, is pierced, and around this hole a recess, *b*, is formed by striking the metal outward to produce a corresponding projection upon the outside.

B is the body of the gudgeon, which is constructed, as seen in Fig. 2, with a head, *d*, the

diameter of the head being somewhat less than the diameter of the recess in the bottom of the cup. Immediately under the head the body is enlarged, as at *e*, the length of the enlargement being considerably greater than the thickness of the metal of the cup. The opening *a* in the center of the bottom of the cup is in diameter substantially that of the enlargement *e*. The gudgeon is introduced through 55 the bottom of the cup, as seen in Fig. 3, to bring the head to a bearing upon the inside, and so that a portion of the enlargement *e* projects upon the outside of the cup, then by suitable dies the enlargement is struck down 60 upon the outside of the cup to form a flange, *f*, around the body and upon the metal of the cup, and so as to firmly clamp the metal between the head *d* and the flange *f*, as seen in Fig. 4. This striking of the flange *f* upon the 65 outside of the cup makes a very strong connection, because of the extent of the flange on one side and the head upon the opposite side, and avoids the use of solder. It is so strong that separation of the gudgeon from the cup 70 is impossible except by the destruction of one or the other. The projection on the outer end of the cup is desirable, but not essential, and is substantially the same as that shown in the 75 patent before referred to.

I am aware that gudgeons have been made by constructing the cup with a concentric recess upon its inside and the gudgeon with a head, the gudgeon introduced from the inside through the central opening in the cup, and 80 so that the head rests in the recess, as seen in Patent No. 298,611, and therefore do not broadly claim such a construction of gudgeon; but in the construction described in that patent the head of the gudgeon is secured in the 85 cup by solder introduced into the recess surrounding the head. Objections exist to such attachment of the gudgeon, in that the gudgeon itself is liable to considerable force longitudinally from the outside, as by supporting 90 the roll on the gudgeon when applying the shade, or for various manipulations, which force tends to break the soldered connection, whereas by constructing the gudgeon with the enlargement *e* and upsetting it upon the outside of the cup so as to form a flange upon the 95 outside and so as to embrace the surrounding 100

metal of the cup between the said flange and the head of the gudgeon, such detachment or breaking of the connection is impossible.

I am also aware that the gudgeon has been 5 riveted into the head by constructing the rivet with a shoulder distant from its inner end so far as to permit that inner end to pass through the central opening in the cup, and then riveting down the inside end; but such riveting upon the inside makes but a slight security.

I claim—

The herein-described improvement in gudgeons for window-shade rollers, consisting in the cup A, constructed with a central opening,

a, at its closed end, combined with the gudgeon 15 B, said gudgeon constructed with the head d upon one end and with an enlargement, e, immediately under the head, the gudgeon introduced through the opening in the cup from the inside outward, to bring the head to a 20 bearing upon the inside of the cup, the enlargement then struck down upon the outside of the cup to form the flange f, substantially as described.

JOHN LINES.
